TOY FLATBED TRUCK

Robert E. De Graw, 13811 116th Ave. NE,
Kirkland, Wash. 98033

Filed Nov. 27, 1972, Ser. No. 309,781

Term of patent 14 years

Int. Cl. D21—01
U.S. Cl. D34—15 AJ

FIG. 1

FIG. 2

FIG. 3

FIG. 4

FIG. 1 is a left side elevational view of a toy flatbed truck showing my new design, the right side being a mirror image thereto;

FIG. 2 is a top plan view thereof;

FIG. 3 is a bottom plan view thereof;

FIG. 4 is a front elevational view thereof;

FIG. 5 is a rear elevational view thereof.

I claim:

The ornamental design for a toy flatbed truck, as shown and described.
